UNITED STATES PATENT OFFICE.

EDDIE ROBINSON AND ALBERT F. ABREO, OF KANSAS CITY, MISSOURI.

DESIGN FOR A WAFFLE-BAKING IRON.

Application filed September 10, 1923. Serial No. 7,176. Term of patent 7 years.

To all whom it may concern:

Be it known that we, EDDIE ROBINSON and ALBERT F. ABREO, citizens of the United States, residing at Kansas City, in the county of Jackson and State of Missouri, have invented a new, original, and ornamental Design for Waffle-Baking Irons, of which the following is a specification, reference being had to the accompanying drawing, forming part thereof.

The figure is a plan view of a waffle baking iron, showing our new design.

We claim:

The ornamental design for a waffle baking iron, as shown.

Dated Kansas City, Missouri, September 6th, 1923.

EDDIE ROBINSON.
ALBERT F. ABREO.

Witnesses:

JOHN C. STEARNS,
ELIAS BERELL.
